UNITED STATES PATENT OFFICE.

ROBERT W. KALTENBACH, OF CLEVELAND HEIGHTS, OHIO, ASSIGNOR TO THE
McMYLER INTERSTATE COMPANY, OF BEDFORD, OHIO, A CORPORATION OF
OHIO.

FLOATING CRANE.

Application filed July 16, 1920. Serial No. 396,741.

To all whom it may concern:

Be it known that I, ROBERT W. KALTENBACH, a citizen of the United States, residing at Cleveland Heights, in the county of Cuyahoga and State of Ohio, have invented a certain new and useful Improvement in Floating Cranes; of which the following is a full, clear, and exact description.

This invention relates to ship cranes, and has for its chief objects to provide a crane having a low center of gravity so that a large load may be lifted through a long radius, and to provide improved mechanism for raising and lowering the boom.

15 The floating crane constituting the subject matter of the present invention is especially designed for handling heavy loads, and the entire structure, including the mounting of the boom and the lifting mechanism, is designed to meet load requirements greater than those for which floating cranes have heretofore been built, and the construction embodying the present invention answers the requirements with high efficiency.

25 The invention may be briefly summarized as consisting in certain novel details of construction, and combinations and arrangements of parts which will be described in the specification and set forth in the appended claims.

In the accompanying sheets of drawings, Fig. 1 is a sectional view through a ship on which my improved crane is mounted, the boom of the crane being shown by full lines in one position, and by dotted lines in its uppermost position and lowermost position; Fig. 2 is a transverse sectional view through the boom just beyond the pair of boom supporting frames and showing the mechanism carried by these frames for elevating and lowering the boom or swinging it about its pivotal axis on the turntable; Fig. 3 is an enlarged side view of one of the boom supporting frames with a part thereof removed; Fig. 4 is a horizontal sectional view through a pair of screws extending lengthwise of each boom supporting frame, and showing the gearing by which the screws are rotated; and Fig. 5 is a horizontal sectional view through a portion of one of the boom supporting frames showing in elevation with parts broken away, a portion of a cross-beam of the boom.

Referring now to the drawings, 10 represents a ship on which the crane is mounted,

which ship may be an ocean going vessel. On the ship is a circular track 11 on which is a turntable 12, mounted to turn about a heavy vertical pin 13 and supported from the track 11 by rollers 14. Mounted on the turntable is a boom 15 of considerable length and width, and formed of suitable structural material, the construction and design being such that heavy loads may be lifted at a long radius. The rear or inner end of the boom is 65 pivotally connected to the turntable by pins 16 supported in suitable brackets close to the turntable so that the center of gravity of the boom is as low as possible. In Fig. 1 three positions of the boom are shown, but it will be understood that it may be shifted to any position intermediate those shown, and it will be observed that when the boom is in its lowermost position it extends horizontally very close to the deck of the boat 10. 75 In this figure the boom is shown at right angles to the axis of the ship, but ordinarily when the vessel is in motion and the crane is not in use, the boom will be swung so as to occupy a fore and aft position. 80

The boom is provided with a fixed hoist indicated generally by the reference character 17, and the fall block and load hook of this hoist are adapted to be raised and lowered by one or more ropes 18 passing about 85 suitable sheaves and about one or more motor driven drums 19 on the turntable. Additionally the boom is preferably provided with a traveling hoist 20 carried by a trolley 21 movable in and out along the lower part 90 of the boom by ropes and one or more motor driven drums 22 preferably carried by the boom. The fall block and load hook of this hoist can be raised and lowered by one or more ropes adapted to be wound about a motor driven drum 23, likewise preferably supported on the turntable as shown conventionally in Fig. 1. 95

Coming now to the mechanism by which the boom is raised and lowered, it will be 100 observed that on opposite sides of the boom are a pair of boom supporting frames 25 which at their lower ends are pivoted at 26 to the turn-table in a manner hereinafter referred to. It will be seen by reference to 105 Fig. 1 that the pivotal connection 16 between the inner or rear end of the boom and the turntable and the pivotal axis 26 of the boom supporting frames are on opposite sides of the center pin 13 of the turn-table, 110

the latter being midway between the axis 16 and the axis 26. These boom supporting frames 25 are likewise built chiefly of structural materials, and the design is such that 5 these frames are capable of transmitting very heavy loads. By reference to Fig. 2 it will be seen that viewed from the front or rear, these boom supporting frames are triangular in shape, and that the outer portions 10 are connected by pins 27 to standards or brackets 28 on the turntable, and that their inner upright portions are connected by hollow pins or trunnions 29 to standards or brackets 30.

15 To support and shift the boom the upright portions of the two boom supporting frames 25 are each provided with a pair of parallel screws 31 which extend nearly the full length of the frames and have their upper ends supported in heavy caps 32 at the top of the boom supporting frames, while their lower ends are journaled in castings 33 at the bottom of the frames. These screws are engaged by traveling nuts 34, having laterally 20 projecting trunnions 34^a which are journaled in so-called beams 35, the construction of which is illustrated in Figs. 2, 4 and 5. Extending centrally through the middle of each beam 35 is a cross-pin 36 on which is supported a heavy strap 37. The lower ends of the straps 37 of the two boom supporting frames are provided with eyes, and they engage reduced ends 38^a of a pair of heavy forgings 38 supported in diaphragms 39 (see Figs. 2 and 5) carried by a cross-beam 40 of the boom 15, this beam 40 extending cross-wise of the boom near the bottom thereof, as best shown in Fig. 2. It will be understood, of course, 25 and it is apparent from the drawings, that the ends of the forgings 38 project beyond both ends of the cross-beam so that their reduced ends 38 may engage the straps 37. It will be understood also, that it is through 30 the cross-beam 40 of the boom the forgings 38 carried thereby, the straps 37, so-called beams 35, nuts 34, and screws 31, that the boom and whatever load may be carried by it are supported.

35 To raise and lower the boom the screws 31 are turned to cause the nuts 34 to travel up or down the screws. The latter are threaded for substantially their entire length, and when the boom is swung to its highest position the nuts are near the upper ends of the screws, and when the boom is in its lowermost position the nuts are near the lower ends of the screws, substantially as illustrated in Fig. 2. Any suitable 40 means may be provided for rotating the screws 31, but in this instance, fixed to the lower ends of each pair of screws are gears 41 which are engaged by a pinion 42 carried by a short vertical shaft 43 journaled 45 in the bottom casting 33 of the boom sup-

porting frame and provided at its lower end with a bevel gear 44 engaged by a driving bevel gear 45. The two bevel gears 45 for driving the screws of both boom supporting frames are preferably mounted on 50 a common cross-shaft 46 which extends through, and is journaled in the hollow trunnions or pins 29 by which the frames are journaled in or pivoted to the lower supports or bases 30. The shaft 46 will be 55 driven by a suitable motor, not shown, carried by the boom, and geared to the shaft. In Fig. 2 one of the driving gears 47 is shown at the middle of the shaft 46.

60 It will be understood that as the nuts travel up the screws, the boom will be elevated, the boom supporting frames then swinging about their lower ends inward toward the center of the turntable, and as the nuts travel down the screws the boom is lowered, the boom supporting frames 35 then swinging toward vertical position. When the boom is in its lowermost position the boom supporting frames are substantially vertical, and in all positions of 65 the boom the boom supporting frames are nearly at right angles to the boom, which is desirable in order that these frames may support the boom and transmit the load to the turntable in the most efficient manner. 70

75 When the laterally projecting forgings 38 travel lengthwise of the supporting frames 25 as the boom is being raised or lowered said forgings are guided in the frames 25 by wheels or rollers 48 which are 80 journaled on the forgings just beyond the ends of the cross-beam 40 and engage parallel guideways or tracks 49 extending lengthwise of the two frames. These rollers 48, the diameters of which are preferably 85 slightly less than the distance between these guideways or tracks 49 also hold the axes of the forgings 38 and hence of the cross-beam 40 centrally of the supporting frames when the boom is stationary, as well as 90 when it is being shifted.

95 In the drawings I have shown, and in the specification I have described only the preferred construction, but it will be understood that the structure is susceptible of 100 modification in details without affecting the principle of the invention, and I aim in my claims to cover all modifications which do not involve a departure from the invention as defined in the appended claims. 105

110 Having described my invention, I claim:

1. In combination with a vessel, a crane comprising a boom pivoted at its inner end, and a boom supporting and boom swinging member pivoted at its lower end and connected to the boom in advance of the pivoted end of the boom, said member having a device adapted to travel up and down along the same to vary the inclination of the boom. 115
2. In combination with a vessel, a crane 120

5 mounted on the vessel and comprising a support, a swinging boom and a boom supporting and shifting frame, the inner end of the boom and the lower part of the frame being 10 pivotally connected to said support on opposite sides of its center, and the frame having a connection with the boom forward of its pivotal connection with the support, said frame having a member adapted to travel up 15 and down the same to vary the inclination of the boom.

3. In combination with a vessel, a crane mounted on the vessel comprising a turntable movable about an axis, a boom and a 15 boom supporting frame, the inner end of said boom and the lower part of said frame being pivotally connected to the turntable on opposite sides of its center, said frame having a connection with the boom in advance 20 of the latter's connection with the turntable, and said frame having a part movable lengthwise thereof to vary the inclination of the boom.

4. A floating crane comprising a platform, 25 a boom having its lowest end pivoted to the platform, a pair of boom supporting members having their lower ends pivoted to the platform and connected to opposite sides of the boom in advance of the latter's connection 30 with the platform, said members having means adapted to travel up and down the same to vary the inclination of the boom.

5. A floating crane comprising a platform movable about a central axis, a boom having 35 its inner lower end pivoted to the platform, a pair of boom supporting and shifting frames having their lower ends pivotally connected to the platform and connected to opposite sides of the boom forward of the 40 latter's point of connection with the platform, and means adapted to travel up and down along said frames for varying the inclination of the boom.

6. A floating crane comprising a turntable 45 adapted to turn about an axis, a boom having its inner end pivoted to the turntable, a pair of boom supporting and shifting frames pivoted at their lower ends to the turntable,

the boom and frames being connected to the turntable on opposite sides of its center, and 50 the frames being connected to opposite sides of the boom forward of the latter's connection with the turntable, and means for shifting lengthwise of the frames the points of connection between the latter and the boom. 55

7. A floating crane comprising a support, a boom pivoted at its inner end to the support, a pair of boom supporting and shifting frames on opposite sides of the boom and pivotally connected at their lower ends to 60 said support, said boom having forward of its point of connection with said support laterally projecting members, and said frames having means movable lengthwise thereof and engaging said members. 65

8. A floating crane comprising a support adapted to be turned about an axis, a boom, a pair of boom supporting and shifting frames, the boom and frames being pivoted to said support on opposite sides of its axis, 70 and the boom having in advance of its connection with said support a cross-beam, and devices movable lengthwise of the frames and connected to said cross-beam.

9. A floating crane comprising a platform, 75 a boom and a pair of boom supporting frames all pivoted to the platform, a cross-beam on the boom in advance of its connection with the platform and having axially projecting studs, screws extending longitudinally of the frames, and members shiftable along said screws and connected to said studs. 80

10. A floating crane comprising a platform, a boom pivoted thereto at its inner 85 end, a pair of boom supporting frames pivoted thereto at their lower ends, supports projecting laterally from the boom forwardly of its point of connection with the platform, screws extending lengthwise of the frames, 90 nuts traveling along said screws, and connecting means between said nuts and said supports.

In testimony whereof I hereunto affix my signature,

ROBERT W. KALTENBACH.
